AIR HEATER

Aubrey H. Robson, Rock Island, Ill., assignor to American Air Filter Company, Inc., Louisville, Ky., a corporation of Delaware

Filed June 5, 1957, Ser. No. 663,795

3 Claims. (Cl. 158—36.6)

This invention relates to a fuel ignition arrangement for oil burning air heaters having a burner of the type generally known as a pot or vaporizing burner.

In the operation of such a pot-type burner, after igniting an initial supply of oil in the pot, additional oil flows into the pot where it is vaporized and ignited by the heat from the burning oil, the combustion process being self-sustaining as long as additional oil is fed to the pot.

One conventional method of initially igniting oil in a pot burner is to insert a burning torch into the pot and hold the torch adjacent the surface of the oil until the oil is vaporized and ignited. The torch may then be withdrawn since the heat from the ignited fuel vaporizes and ignites additional oil flowing to the pot. This torch method of ignition is objectionable because: the fuel tank is often used as a source for saturating the torch, this practice sometimes resulting in particles being dislodged from the torch and ultimately clogging the fuel supply line; there is a certain amount of danger inherent in handling a flaming torch; and, if the fuel is cold, it may take a relatively long time to ignite it. Thus, there have been a number of ignition arrangements devised, but such arrangements are typically complicated and expensive in relation to the cost of the heater.

Therefore, it is the principal object of this invention to provide an ignition system for pot burners which is simple and inexpensive.

A further object is to provide an ignition system which may be operated to quickly and conveniently ignite the fuel in the burner.

In accordance with my invention, I mount an ignition chamber on the outer side of a circumferential wall of a conventional pot burner so that the interior of the chamber is in open communication with the interior of the burner. A spray nozzle mounted in the outer side wall of the ignition chamber is arranged to discharge a spray of fuel particles into the pot when fuel is supplied under pressure to the nozzle. A fuel supply conduit interconnects the inlet of the nozzle to a fuel supply conduit and a manually operated fuel pump is interposed in the supply conduit between the fuel source and the nozzle so that the pump, when operated, will deliver fuel under spray producing pressure to the nozzle. A fuel igniter is mounted in a wall of the chamber with the igniting element thereof positioned in igniting proximity to the path of spray discharge from the nozzle so that when the fuel igniter is connected to an electrical energy source, the igniting element will operate to ignite the fuel particles being discharged into the burner by the nozzle.

The invention is illustrated in the accompanying drawing wherein:

Figure 1 is a partly broken elevational view of a heater having a pot burner and showing, in somewhat diagrammatic form, the fuel system and ignition arrangement;

Figure 2 is a horizontal section taken along the line 2—2 of Figure 1.

Referring to the drawing, the combustion chamber includes a cup-shaped pot 1 having a vertical circumferential

2

side wall, also designated 1, and a horizontal bottom wall or floor 2. The side wall 1 includes holes 3 for the admission of air for combustion purposes, and the floor 2 is provided with a central opening to accommodate the outlet end of a combustion air duct 4. The pot is concentrically positioned in nesting relationship in an outer cup-shaped shell 5 of somewhat greater diameter and height, the circumferential side wall 5 of the shell forming with the pot wall 1 a vertical annular chamber 6 which is in communication with the outlet end of duct 4 by virtue of the open space 7 between pot floor 2 and the shell floor 8. Combustion air from the outlet of duct 4 flows radially outward to the annular chamber 6 and thence through the holes 3 into the pot to support combustion.

A heat exchange chamber 9, in the form of a cup of larger diameter than the shell 5, is mounted in inverted position above the combustion chamber. It includes a circumferential side wall 9, a horizontal top wall 10, and an annular flange 11 extending inwardly from its lower rim to the upper rim of the pot, this annular flange providing a top closure for the annular chamber 6. An exhaust stack 12 is connected to the upper portion of the chamber for the purpose of conveying combustion gases to a disposal point.

A draft of combustion air is created at the inlet end of duct 4 by a centrifugal blower 13, and a draft of ventilation air is created by axial fan 14, the fan and blower both being driven by electric motor 15. The ventilation air flows around the heat exchange chamber in the direction of the arrows in Figure 1, the ventilation air picking up heat from the exchanger as it flows around the outside surface thereof. To direct the air around the heat exchanger, and to insure that it will pass closely adjacent to the outside surface thereof, a casing 16 is provided, the casing having an inlet opening to accommodate the axial fan, and a suitable outlet opening on the opposite side of the heat exchanger.

A supply of liquid fuel such as oil is contained in tank 17 which is interconnected by conduit 18 to a fuel inlet opening adjacent the floor of pot 1. A conventional valve 19 for regulating the flow rate is provided in the conduit 18.

The ignition chamber 20 is a separate box-like compartment having an open inner-end mounted on the side wall 1 of the pot, the portion of the pot wall bounded thereby being cut-out so that the interior of the pot and the ignition chamber are in open communication. The ignition chamber protrudes outwardly through the wall 5 of the outer shell so that the outer end of the chamber is easily accessible for mounting the ignition system components. The edges of the opening in side wall 5 through which the chamber projects are preferably welded or otherwise secured to the intersecting walls of the ignition chamber to effect a seal which prevents the escape of combustion air from the annular chamber 6 to atmosphere.

The closed outer-end wall of the ignition chamber carries a spray nozzle 21 which projects through the wall with its outlet within the chamber and directed towards the interior of the pot so as to discharge a spray of relatively fine fuel particles or droplets when fuel is supplied under pressure to its inlet, which is outside the outer-end wall and interconnected by conduit 22 to the supply conduit 18.

A conventional priming-type hand pump 23 is interposed in conduit 22 to receive fuel and force it under pressure to the nozzle when the pump plunger is manually operated. The inlet and outlet valves within the pump are arranged so that they close to prevent the flow of fuel through the pump when the pump is not being operated.

The top wall of the ignition chamber carries an igniter, such as glow-plug 24 which has its resistance element positioned within the discharge path of the spray emanating from the nozzle, and its electric terminal located on the outside of the chamber. The terminal is connected by electrical conductor 25 to one side of an electrical energy source, shown as battery 26, which has the other side grounded on the framework of the heater. An electric switch 27 provided in conductor 25 may be opened to interrupt the flow of current after the fuel in 10 the pot has been ignited.

The battery 26 should possess sufficient power to quickly heat the resistance element to a temperature which will vaporize and ignite the spray particles which strike it. A six volt battery of the type commonly known as a "Hotshot" will operate quite satisfactorily in my arrangement to furnish current to the plug.

Operation

To institute heater operation, the valve 19 is placed in 20 an open position until a limited quantity of fuel flows through conduit 18 onto the floor of the pot to form a pool. The valve 19 is then placed in a closed position until this pool has been ignited.

The switch 27 is closed so that electric current will 25 flow through conductor 25 to the resistance element of plug 24, thereby causing it to heat up to its operating temperature after a short interval. The pump 23, which is located for easy accessibility, is then manually operated to pump fuel under pressure to the nozzle 21. The pressurized fuel is discharged in a spray from the nozzle outlet towards the interior of the pot.

Since the particles of fuel forming the spray are relatively minute, any particles which strike the high temperature resistance element are vaporized and ignited upon contact therewith. These burning particles in turn vaporize and ignite adjacent passing particles until a substantial portion of the particles are ignited. This results in a 30 burning spray being directed onto the surface of the fuel on the floor of the pot.

The spray continues to burn after alighting on the pool in the pot, and after a sufficient number of spurts of burning fuel have been introduced, particles of fuel forming the top surface of the pool are heated, vaporized and ignited. When this occurs, the switch 27 may be 35 opened, the operation of pump 23 discontinued and valve 19 opened, since the combustion process is self-sustaining as long as fuel continues to flow through conduit 18 to the pot.

The operation of the electric motor 15 is started while the pump is being operated so that sufficient air to support combustion will be delivered through duct 4 to the pot interior, and so that the heat received by the walls of the heat exchange chamber 9 is carried away by the 40 ventilation air passing therearound.

Miscellaneous

It will be noted that the bottom wall of the ignition chamber is sloped downwardly from adjacent the nozzle to the pot wall so that any fuel which drips from the nozzle after the pump operation is stopped will flow into the pot. This prevents such fuel from burning while still in the chamber, and minimizes the possibility of the resistance element and nozzle being fouled by the combustion products resulting therefrom.

It will be appreciated that, although the electrical power source and igniter have been shown and described as a battery and glow-plug respectively, my invention contemplates the possible use of equivalent elements affording equally satisfactory results. Since these heaters are frequently constructed to utilize either an electric motor or gasoline engine for driving the fans and blower, it will be readily appreciated that either the power source for the electric motor, or electric power generated by a conventional generator mounted on the gasoline engine

may be used, instead of a battery, as the electrical power source for the ignition arrangement.

A low voltage transformer connected to the electric motor power line may be utilized to furnish current to a glow-plug or, if a spark plug is the igniter, a conventional spark discharge transformer on the power line may be used to provide the requisite voltage. If a gasoline engine is used to power the fans and blower, such an arrangement being commonly used where there is no readily available power line, a conventional magneto system may be employed to furnish a voltage sufficiently high to spark a conventional spark-gap type of plug. It is preferred however, to use a self-contained source of electrical energy such as a battery, and a resistance type igniter such as a glow-plug, since with this arrangement it is not necessary to change the circuit or igniter if the fan and blower power source is changed on a heater operating in the field.

Having described my invention, I claim:

1. In a vaporizing fuel burner of the pot type having an inner pot disposed within an outer shell to form an annular space between the walls of said pot and said shell and through which space combustion air flows into said pot, fuel ignition and control apparatus comprising: a fuel tank containing a source of fuel of the type normally adapted for use in said pot type burner, said tank being disposed above said pot for providing gravity flow of fuel during normal burner operation; a first fuel conduit connected between said tank and said pot and including a valve means for controlling gravity fuel flow in said first conduit, an ignition chamber having an open inner end mounted over an opening in the side wall of said pot to place the interiors of said pot and chamber in open communication, said ignition chamber extending outwardly through said annular space and said shell in sealed relationship to provide an air tight outer portion of said chamber external to said shell and remote from combustion in said pot; a second fuel conduit having one end connected to said tank and the other end to nozzle means mounted in the end wall of said chamber outer portion in a position to direct a spray of relatively fine particles through said open inner end of said chamber into said pot when fuel is supplied under pressure to said nozzle means; manually operative pump means in said second conduit and adapted to be operated to supply fuel to said nozzle means under a spray producing pressure; a fuel igniter mounted in said outer portion of said chamber with its fuel igniting element disposed in the path of a portion only of said spray to provide vaporization and ignition thereof as said spray is discharged from said nozzle means; and, means for electrically energizing said fuel igniter for igniting the spray of fuel discharged into said pot.

2. In a vaporizing fuel burner of the pot type having an inner pot disposed within an outer shell to form an annular space between the walls of said pot and said shell, fuel ignition and control apparatus comprising; fuel tank means containing fuel of the type normally adapted for use in said pot type burner, said tank means being mounted above said pot for providing gravity flow of fuel during normal burner operation; a first fuel line connecting said tank means and said pot and including a valve for controlling gravity fuel flow in said first line, an ignition chamber having an open inner end mounted over an opening in a side wall of said pot to provide interior communication between said pot and said chamber, said chamber extending outwardly through said space and said shell in sealed relationship to define an outer portion external to said shell; a second fuel line having one end connected to said tank means and the other end to nozzle means mounted in the end wall of said chamber outer portion in a position to direct a spray of relatively fine particles through said open inner end of said chamber into said pot when fuel is supplied under pressure to said nozzle means; manually operative pump means in said

second fuel line and adapted to be operated to supply fuel to said nozzle means under a spray producing pressure; a fuel igniter mounted in said outer portion of said chamber with its fuel igniting element disposed in the path of a portion only of said spray to provide vaporization and ignition thereof as said spray is discharged from said nozzle means; and, means for electrically energizing said fuel igniter for igniting the spray of fuel discharged into said pot.

3. The fuel burner of claim 2 wherein said chamber

includes: a bottom wall sloping downwardly from said outer end wall toward said pot.
